UNITED STATES PATENT OFFICE.

AUGUST J. KREUZKAMP, OF CHICAGO, ILLINOIS, ASSIGNOR TO ENGLANDER SPRING BED COMPANY, OF BROOKLYN, NEW YORK.

BED OR COUCH-BED.

1,368,509.

Specification of Letters Patent. Patented Feb. 15, 1921.

Application filed August 24, 1916. Serial No. 116,583.

To all whom it may concern:

Be it known that I, AUGUST J. KREUZKAMP, a citizen of the United States, residing at Chicago, in the county of Cook and State of Illinois, have invented certain new and useful Improvements in Beds or Couch-Beds, of which the following is a specification.

This invention relates to an improvement in beds or couch beds, the object of the invention being to provide an improved knock-down bed, comprising a head, a foot and a bed bottom or spring mattress section or supports detachably connected to the head and foot in an improved manner, whereby the structure is simple in construction, durable and rigid in use and can readily be set up or knocked down; while at the same time it is very inexpensive to manufacture.

A further object of the invention is the provision of an improved bed of the class described in which the bed bottom or spring mattress section is connected with the head and foot members at the top and bottom of the bottom or spring.

In the drawings accompanying and forming a part of this specification Figure 1 is a longitudinal sectional view of this improved bed; Fig. 2 is a perspective view of the spring mattress frame detached from the head and foot; Fig. 3 is a detailed view, illustrating the manner of connecting the spring mattress section with the head or foot; and Fig. 4 is a partly sectional view at right angles to that of Fig. 3.

Similar characters of reference indicate corresponding parts in the several figures of the drawings.

In the preferred form thereof shown this improvement comprises a head 2 and a foot 3, each of which in the present instance consists of a pair of legs 4 connected by a cross member 5. Each leg is provided on its inner side at a predetermined distance below the top of the spring with inwardly extending headed pins 6, and at a point adjacent to the top of the spring with a swinging hook 7, each pivotally secured to the leg on that side thereof, which is inside relative to its companion leg. The spring mattress frame comprises a pair of end members 8 to which a spring fabric 9 is connected in the usual manner and each of these end members shown in the present in-

stance as formed of angle iron is provided with a depending portion 10, the depending portions on each side being suitably connected by side bar 11 for maintaining the ends properly spaced apart when the spring fabric is stretched therebetween. Each of these depending ends is provided with a notch or slot 12 for the reception of the headed pins hereinbefore referred to carried by the legs of the head and foot.

From the foregoing it will be observed that the detachable mattress section is connected with the head and foot at the bottom thereof relatively remote from the top by simple pin and slot connections, and at the top by simple hooks which hook over the cross angle members of the bed bottom or mattress section which supporting bottom of course can be formed of any suitable material as metal or otherwise, whereby on raising the hooks the detachable spring mattress section can be readily released from its pins by slightly swinging the head and foot and lifting each end from the head and foot respectively. As the hooks extend over or into the framework comprising the side bars 11 and cross bars 8, to which the spring or bed bottom is connected, and between which it is stretched, they act to wedge this framework, forming the third member or spring of the structure into tight engagement with the other two members, the head and the foot, and so prevent any shaking or wobbling joints.

I am aware that it is not new to make a three part bed structure, but in none of these old structures of which I am aware is the spring mattress section connected with the head and foot at the top and bottom of the spring mattress by two entirely different kinds of connection, one of which is releasable prior to the other, and one of which in the present instance is shown as a pin and slot connection and the other of which is shown as a shiftable or swinging hook connection, whereby on the mere lifting of the hook the spring mattress section or the spring mattress supports or side bars which carry such spring mattress may be readily detached from the foot or head without the necessity of maintaining the head or the foot, as the case may be, and the spring mattress section in parallel juxtaposition so as to enable the mattress section to be slid upward and then removed.

In other words, in the present improvement it will be observed that by merely first releasing or swinging the hooks 7 away from the cross angle bars 8, the head or foot 5 can be swung away from the mattress section to facilitate the lifting of the latter from the pins 6, whereas if a pin and slot connection similar to that shown at 6 were substituted for the hook shown at 7, the 10 result would be that in order to lift the mattress section it would be necessary to slide the mattress section upward relatively to the head or the foot, while maintaining the head or foot in parallel relation with 15 the end of the mattress section, a rather difficult thing for one person to do with a heavy structure of this kind, especially as such pin and slot connection frequently sticks or binds. In the present improvement, however, the hooks are shifted before the mattress section is handled and then the head or foot can be swung away from the mattress section so that it is not necessary to maintain it in parallel relation 20 with the end of the mattress section in order to disconnect the pin and notch connection, and this swinging movement of the head or foot tends to loosen the pin and notch connection, and so relieve any 25 binding or sticking action at this point, so that the mattress can be readily and easily lifted.

By means of the present improvement one mattress section can be readily inter- 25 changed with the head and foot of another without being specially fitted thereto, whereas in all three part structures with which I am familiar the spring section always has to go with its particular head 40 and foot since they are specially fitted for each other.

I claim as my invention:

1. A knock-down three-part bed structure comprising a head and a foot, a detachable bed bottom mattress frame comprising side 45

bars, end bars and a fabric therebetween, said frame connected at its top and bottom and at each corner thereof with said head and foot by sliding connections at one point and swinging hook connections at another, 50 the latter hooking over the top of the end bars and wedging the frame into engagement with the head and foot and releasable prior to the other connection.

2. A knock-down three-part bed structure 55 comprising a head, a foot, and a detachable bed bottom comprising a permanently connected framework consisting of a pair of end bars, a fabric stretched therebetween and side bars permanently connected with 60 said end bars for maintaining them spaced apart, said bed bottom having connection with the head and foot at each corner thereof by a pair of differently formed connections, one releasable prior to the other, 65 one of each pair comprising a sliding connection and the other located thereabove and comprising a swinging hook in position to hook into said framework at the end thereof substantially directly above 70 said first connection and effective to wedge the bed bottom into engagement with the head and foot.

3. A knock-down bed structure comprising a head and a foot, a detachable bed 75 bottom section comprising a pair of connected end members, each consisting of an angle iron cross member having depending portions, each of said depending portions having at its lower end a notch, headed 80 pins carried by the head and foot for the reception of said notches, and swinging hooks carried by said head and foot members for engaging said detachable bed bottom section at a point substantially directly 85 above the pin and notch connection.

Signed at Chicago, in the county of Cook and State of Illinois, this 15th day of August, 1916.

AUGUST J. KREUZKAMP.
